UNITED STATES PATENT OFFICE.

TAYLOR M. CAIN, OF OGDEN, UTAH.

AUTOMATIC CROSSING BLOCK FOR RAILWAYS.

Application filed March 28, 1927. Serial No. 179,657.

This invention pertains to means for protecting railway crossings from accident, and seeks to provide automatic means for operating safety signals and safety devices for 5 the purposes set forth.

More specifically the invention provides for automatically operated gates to be closed or dropped at the crossing, together with signal bells to be rung at the time the said 10 gates are closed, together with means carried by the gates to render them visible at night.

The invention depends upon electrical operation of various units of the system, the 15 said electrical operation being set in motion when the train enters the block in question and which is broken when the train leaves the said block. When the train is off the block in question the circuit through the 20 various electrical units is broken open, being closed when the train is on the block, the wheels of the train passing over the rails forming the means for closing the said circuit.

25 The invention is illustrated in the accompanying drawings, in which,

Figure 1 represents a perspective view showing the gates closed and the bells in position,

30 Figure 2 is a wiring diagram illustrating the connections with the various units,

Figure 3 is an elevation of one of the gates showing the arrangement of lights carried to the gates to render the gates visible at night,

Figure 4 is a plan view showing the gate and operating mechanism,

Figure 5 is an elevation of the gate itself,

40 Figure 6 is a section on the line 6-6 of Figure 4 looking in the direction of the arrows,

Figure 7 is a section taken on the line 7-7 of Figure 5, and

45 Figure 8 is a sectional view showing the automatic switch employed in raising and lowering the gate.

Referring to the drawings it will be seen that the system comprises gates "G" which may be of the usual drop gate type, or any 50 other form adapting to bar the roadway at the crossing, these gates being intended to be electrically operated by the source of current B', which is any convenient source, or it may be a battery of either the storage 55 or dry battery type, or any other generator of current. Gates G are operated by the mo-

tor M, connected with the gate by means of a suitable connection such as gear wheels, as shown in Figure 4, the operation of the motor resulting in the dropping of the gates 60 G. In order to assure the stoppage of the gate mechanism when the gates have been put in place, there is provided a switch S' which is adapted to be struck by the gate upon its descent thereby breaking the contact through the motor and stopping the same when the gate is dropped. The switch comprises the contact member S' which may be carried upon a metallic leaf or spring carrying a contact c. When the switch is 70 closed this contact c engages the contact c' which is secured to the housing of the switch box (see Figure 8). The construction of this switch is such that when the gate is raised by means of the counter-weight C 75 after the train has passed, the spring of the switch will cause the contacts c and c' to again engage each other and permit the current to flow for the further actuation of the motor. The contact member S' of the 80 switch is pulled up by the spring member as the gate rises, the switch being closed in operated position.

In order to hold the gates in place there is provided a pawl P which is adapted to 85 engage a ratchet R carried by the gate G. This pawl is operated by a solenoid S, the coil of which is magnetized when the circuit is closed thereby causing the pawl to engage the ratchet of the gate and to hold the gate 90 in position. When the circuit becomes broken the coil S becomes demagnetized and the spring s pulls the pawl back out of contact with the ratchet R of the gate, the gate being therefore free to spring upward. 95

When the gates are lowered their position will be visible by the provision of lights L carried by the gates. Bells B are also connected to the same source of current and further serve as a warning signalling when 100 the gates are closed, which signal will be audible not only when approaching the crossing, but when the said crossing is reached. The provision of the bells, while desired, is optional. 105

The operation of the device is brought about by a train passing into the block in which the present invention is located, this block being shown in Figure 2 by the provision of track insulations I which separate 110 this block from the remainder of the track. The circuit is normally open, but as will be

seen from Figure 2 the connection of the circuit together with the connection of the units of the system with the rails are such that as soon as the wheels of the train pass over the 5 track insulation I, the circuit will be closed through the rails and the various units of the system will be operated. The motor M will be set into action which causes the dropping of the gates G, the bells B will be rung, the 10 solenoid magnetized, the motor M deenergized and the gates held into position, as previously described. As soon as the train passes the solenoid circuit is again broken, the gates G are raised by their counter-weight C, 15 the pawl P having been withdrawn by the operation of the spring s with the demagnetization of the coil S. It will be apparent from the drawings that the pawl P is pivoted at its lower end to the support so 20 that it is free to move backwards and forwards to secure and release the gates at the proper time.

The gates G are of hollow formation and are provided with window openings 10 upon 25 opposite sides thereof in transverse alignment with the lights L. Overlying these openings are transparent panes 11, the latter being held to the gates by clips 12. As

illustrated in Figure 7 the lights L are supported upon inverted channel shaped plates 30 13 whose parallel legs are disposed against the side walls of the gates and are secured thereto by transverse fastenings 14 which pass through and engage certain of the 35 clips 12.

I claim:

In combination a pivotally supported counterbalanced crossing gate normally disposed in a vertical position, operating means 40 for moving the gate to a horizontal position, a solenoid supported to one side of the gate whose armature is pivoted to move towards and away from the gate and having ratchet teeth upon one face thereof, a spring normally urging the armature away from the 45 gate, a lug on the gate engageable by the ratchet teeth to retain the gate in horizontal position, and electrical means operable by an approaching train to magnetize the solenoid to engage the ratchet teeth with the lug, the 50 spring functioning to disengage the ratchet teeth from the lug and permit return of the gate to normal position after the train has passed beyond the gate.

TAYLOR M. CAIN.
